UNITED STATES PATENT OFFICE.

TERJE AANENSEN FIDJELAND, OF FOSTVEDT, IVELAND PR CHRISTIAN.
SAND S., NORWAY.

MAGAZINE-RIFLE.

SPECIFICATION forming part of Letters Patent No. 691,369, dated January 21, 1902.

Application filed April 19, 1901. Serial No. 56,621. (No model.)

To all whom it may concern:

Be it known that I, TERJE AANENSEN FIDJELAND, a citizen of the Kingdom of Norway, residing at Fostvedt, Iveland pr Christian-sand S., Norway, have made certain new and useful Improvements in Magazine-Rifles, of which the following is a specification.

The requirements which nowadays are made in regard to a magazine-rifle, especially for military use, are many and considerable ones. It is required that the different parts under quick fire of the soldier shall work certainly and easily in combination with a magazine of as large capacity as possible, that the number of the parts shall be a minimum, that each single element in the mechanism can execute the greatest possible number of actions, and that the whole mechanism, with its different parts, shall be fitted together in such a manner that it can be separated in a moment for cleaning, &c., with the help of the hand only and without necessitating the use of extra tools or time-losing and difficult joining work, and, finally, that all the coacting parts through the violent strain, for instance, of a quick fire must be absolutely rigid and work reliably. The solution of these problems in the greatest possible degree is the object of the present invention, which will now be more particularly described.

The most essential feature of this rifle is that the magazine—the so-called “rotary magazine”—by its feed mechanism feeds the single cartridges on a circular course, that the feeding in itself becomes as practical as it can possibly be made, while the magazine is able to contain a maximum number of cartridges without its size in any way disturbing the rifle-body and without any projecting part, causing inconvenience under the manuals or the use of the rifle in general. The internal mechanism of the rifle is simple, solid, and effective, and its outer appearance resembles in its closed and compact condition that of a simple and light single-loading rifle.

The invention is represented in the accompanying drawings, in which—

Figure 1 is a sectional elevation of the rifle during the process of loading. Fig. 2 is a plan view. Fig. 3 is a longitudinal sectional view of the breech-block. Fig. 4 is a rear

view of the same. Fig. 5 is a section on line I I of Fig. 3. Fig. 6 is a longitudinal section of the frame and the magazine. Fig. 7 is a similar view partly in side elevation. Fig. 8 is a plan view of the parts shown in Figs. 6 and 7. Fig. 9 is a horizontal section of the same; Fig. 10, a section through the frame on the line II II, Fig. 6; Fig. 11, a section through the frame on the line III III, Fig. 6; and Fig. 12, a section through the frame on the line IV IV, Fig. 6.

The only parts of this rifle which cannot be taken apart without the gunsmith are the two main parts—the frame A and the barrel B— while all the other separate parts can be taken apart and joined again by any one without the least study and without risk of an incorrect reassemblage. The magazine itself, with its feed mechanism, which is the most essential part of the invention, will be described first. It consists of a semicircular box somewhat tapering in the longitudinal direction of the rifle, the bottom of which is covered by the loose semicircular casing 1, which is held fast at one end by a tongue and groove and at its other end by the catch 2. The magazine has two end pieces 3 and 4, of which the latter is double, and which pieces form part of the frame of the rifle. The shape of the magazine in transverse section is best visible in Fig. 12. Within this circular magazine-chamber 5 the cartridges α are placed after having been filled in through the opening closed by the cover 6. When the rifle is fired, the cartridges traverse a circular course to and through the opening 7 to the receiver in front of the breech-block and are passed singly into the cartridge-chamber of the rifle.

The automatic feed mechanism, which comes into effect when the cover 6 is closed, will now be described. This consists, as best can be seen from Figs. 6 and 12, in its leading features of a revolving central hollow cylinder 8 with a tangential wing 9, which is the real feeding part. The cylinder 8 is, as Fig. 12 shows, hollow and incloses a spiral spring 10, which constantly presses against a piece 11, which by means of a tongue and groove is lengthwise movable in the longitudinal direction of the cylinder and has a pivot 12. The cylinder 8 has on its other end a fixed cog-

wheel 13, and when everything is brought in its right place, as shown in Figs. 6, 11, and 12, the pivot 12 engages in a corresponding hole in the one end piece 3 and the cog-wheel 13 in the chamber 14, which is formed between the double end 4. Consequently the forward and backward springing piece 11 will constantly secure the position of the cylinder 8 without any risk of its coming loose through wear and tear. Be it understood that this same springing piece 11 renders possible the quick and convenient insertion of the cylinder 8 between the ends 3 and 4. In the frame A is loosely inserted with its pivot 15 a semi-circular blade-spring 16, Fig. 11, which with its free end constantly presses against the piece 18, which turns on a pivot 17, which piece 18 has a projection 19 and a cog-segment 20, which latter gears in the cog-wheel 13 on the cylinder 8. The cover 6, which closes the loading-opening of the magazine, turns on pivots 21 and is controlled normally by the small blade-spring 22, Figs. 7 and 12, which is inserted in the semicircular casing 1. The cover 6 has two teeth or bosses 23 24, which engage on opposite sides of the projection 19 for the purpose of operating the segment 18 upon opening and closing the magazine-cover. When now the cover 6 is opened for the filling in of cartridges, the tooth 23 will revolve the piece 18, by which its row of teeth 20 revolve the cylinder 8, so that it, with its wing 9, is pushed into the position shown in Fig. 12, and is here held in position as long as the cover 6 is open, so that the magazine can be filled, for instance, with eight cartridges while the rifle is held in such a turned position that the cartridges are simply rolled down into the magazine. When the cover is closed, the rounded face of the projection is removed from contact with the rounded face of the projection or part 19; but the filled cartridges will prevent the return of the cylinder and segment by bearing against the arm 9, and thus holding it in the position shown in Fig. 12. At the same time the spring 16, bearing against said segment, tends constantly through the gearing to rotate the cylinder and arm against the resistance of the cartridge 50 and to move the said cartridges as fast as the preceding ones are introduced into the firing-chamber.

Should it be wished to disconnect the magazine and use the rifle as a single-loader, this is done by simply turning a lever 25, which is fastened on a small pin or axle 26, Figs. 9, 10, and 11, which extends in a longitudinal direction into the rifle and lies exactly in line with the entrance 7 of the cartridge, but is here formed semicylindrical, so that the axle 26 when it lies in the position as shown in Fig. 9 allows the passage of the cartridges from the magazine, but by turning about one hundred and eighty degrees will place its semicylindrical part in the opening, so that the opening 7 is thereby contracted so much that the passage of the cartridge is prevented.

The breech-block is a collective designation for those parts which together associate in a movement in the lengthwise direction of the rifle each time a new cartridge is to be passed from the magazine into the barrel to be fired and afterward to be extracted and ejected. This is clearly represented in Figs. 1, 2, 3, 4, and 5 of the drawings. It consists of the breech-block body itself 27, which bears the operating-lever 28. The breech-block 27 has also a number of bosses. The drawings show three pieces 29 30 31, situated at somewhat various angles to one another and which when the rifle is ready for firing—in other words, locked—engage in the corresponding recesses 32 33 34, Fig. 9, and thus serve to take up the recoil under firing. In the same manner also the lever 28 works, which then is pushed down into the recess 35 to bar the mechanism, as already known and used in most magazine-rifles now in use. At the same time it is to be mentioned that this rifle possesses as many as four recoil-blocks. The breech-block when the lever 28 is thrown up may be propelled forward and backward in the receiver. When it is moved backward, the opening 7, Fig. 12, from the magazine is uncovered and a cartridge is delivered partially into the receiver 95 by the wing or cartridge-feeder 9. When the breech-block is pushed forward again, this cartridge passes into the chamber 36, as Fig. 1 shows. This will be understood without further explanation. When the lever 28 is subsequently pushed down into the notch or recess 35, the rifle is bolted. On the other hand, the extractor mechanism of the breech-block has a novel feature and will therefore be described more in detail. The extractor 105 is composed of the springing arm 45, which is connected to the breech-block by the pin 44 and which in the bolted position of the rifle completely fills the only opening 46 of the receiver, Fig. 8, so that consequently not only 110 the receiver, but the magazine and all the parts of the breech-block as well, are entirely closed against dust and damp. (See Fig. 2.) This extractor-arm 45 has on its front end the fixed-extractor-hook 47, which when the rifle 115 is bolted and loaded engages in the groove on the rear of the cartridge 50. (See Fig. 1.) To further insure the engagement of the hook in the groove of the cartridge, it is supplied with a leaf-spring 48, placed in a track 120 49 in the fore part of the arm 45 and bearing on its outer springing end a projection 50. In the hind part of the rifle-barrel B, close to the chamber, a recess 51 has been provided, which recess corresponds to the hook 47, and 125 when the breech-block is forced forward into its locked position the extractor-hook 47, assisted by the spring 50, will be forced to engage securely in the groove of the cartridge, and thereby on the opening of the breech-block effect the extraction of the cartridge 130 with certainty.

52 is the ejector of the rifle, which turns on the pivot 53 in a notch in the bottom of the

5 receiver and effects the ejecting by causing the arm 52 to turn up when the foremost small stop 54 of the breech-block 27 strikes against the hinder upwardly-bent end 55 of the arm 52, and thereby throws out the cartridge-shell, which until now has been held fast by the extractor 47.

10 56 is the trigger-guard, which, with a hook 57, extends into an opening in the magazine end 4 and which is held in position by a screw-bolt 59, which is screwed through the grip 58 of the stock and into the frame, and thereby also holds the frame fixed to the stock. This bolt 59 is the only screw of the rifle.

15 Having now described my invention, what I claim as new, and desire to secure by Letters Patent, is—

20 1. In a magazine-rifle as set forth the magazine consisting of the circular magazine-chamber 5 the one side of which corresponds with the breech through an opening 7 and the other side of which has a spring-influenced cover 6 for filling of the cartridges *x*, and which chamber 5 in its central part has a hollow cylinder 8 which in the longitudinal direction is springingly supported and in the rotary direction is spring-influenced, and which cylinder 8 has a tangential wing 9 that serves as cartridge-feeder.

25 30 2. In a magazine-rifle the combination with the frame having integral single and double depending walls forming the end walls of the

magazine, of a semicylindrical cover forming the bottom of the magazine, a tongue-and-groove connection between said cover and 35 one of the end walls, and a spring-catch engaging the opposite end of the cover for holding it removably in place, substantially as described.

3. In a magazine-rifle, the combination with 40 the magazine of a cylinder 8 therein, a sliding piece 11 in the end of said cylinder having a pivot engaging the end wall of the magazine, a spring exerting tension on said sliding piece, said cylinder at its opposite end 45 being journaled in the other end wall of the magazine, a cog-wheel carried by said cylinder, a rocking toothed segment engaging said cog-wheel, a spring exerting tension on said segment and tending through the gearing to 50 rotate said cylinder, a cover for closing the filling-opening to the magazine, means whereby the opening of the cover swings said segment against the tension of the spring, and a feeding-wing carried by said cylinder and 55 operating under the action of the spring and segment to feed the cartridges when the cover is closed, substantially as described.

In witness whereof I have hereunto set my hand in presence of two witnesses.

TERJE AANENSEN FIDJELAND.
